(57) **CLAIM**

The ornamental design for an architectural fixture, as shown and described.

DESCRIPTION

FIG. 1 is a bottom, front, right perspective view of an architectural fixture according to a first embodiment of our new design;

FIG. 2 is a top plan view thereof;

FIG. 3 is a front elevation view thereof;

FIG. 4 is a right side elevation view thereof;

FIG. 5 is a rear elevation view thereof;

FIG. 6 is a left side elevation view thereof;

FIG. 7 is a bottom plan view thereof;

FIG. 8 is a top, front, right perspective view thereof;

FIG. 9 is an enlarged section of FIG. 2 taken along line 9 of FIG. 2;

FIG. 10 is an enlarged section of FIG. 2 taken along line 10 of FIG. 2;

FIG. 11 is an enlarged section of FIG. 2 taken along line 11 of FIG. 2;

FIG. 12 is a bottom, front, right perspective view of an architectural fixture according to a second embodiment of our new design;

FIG. 13 is a top plan view thereof;

FIG. 14 is a front elevation view thereof;

FIG. 15 is a right side elevation view thereof;

FIG. 16 is a rear elevation view thereof;

FIG. 17 is a left side elevation view thereof;

FIG. 18 is a bottom plan view thereof; and,

FIG. 19 is a top, front, right perspective view thereof.

The appearance of any portion of the architectural fixture between the break lines forms no part of the claimed design. The broken lines are for the purpose of illustrating portions of the architectural fixture that form no part of the claimed design. The dot-dash lines define the bounds of the architectural fixture and also form no part of the claimed design.
